[57] CLAIM

The ornamental design for a cover, as shown and described.

DESCRIPTION

FIG. 1 is a three quarter view of the design showing the cover and the top portion of a bottle therein. The bottle, shown in dashed lines, is not part of the design.

FIG. 2 is a view of the cover taken from a position opposite to FIG. 1;

FIG. 3 is a view of the cover of FIG. 1 in an open position with the bottle removed;

FIG. 4 is a top view of the cover of FIG. 1;

FIG. 5 is a bottom view of the container and insulated cover of FIG. 1;

FIG. 6 is similar to FIG. 1, but shows interlineations to

indicate a contrast in colours; and,

FIG. 7 is similar to FIG. 2, but shows interlineations to indicate a contrast in colour.
